UNITED STATES PATENT OFFICE.

JOHN BLISS, OF LONDON, ENGLAND, ASSIGNOR TO C. C. WAKEFIELD & COMPANY
LIMITED, OF LONDON, ENGLAND, A BRITISH COMPANY.

LUBRICATING SYSTEM.

1,411,202.

Specification of Letters Patent. Patented Mar. 28, 1922.

Application filed August 5, 1921. Serial No. 490,031.

To all whom it may concern:

Be it known that I, JOHN BLISS, a subject of the King of England, residing at London, England, have invented certain new and useful Improvements in Lubricating Systems, of which the following is a specification.

This invention is for improvements in or relating to lubricating systems of the type wherein steam is supplied to oil-feed conduits and mixes therein with the oil that is being supplied through it under pressure by a pump.

This invention has for its main object to provide that the steam shall be automatically admitted to the oil when the pump is operating and automatically cut off when it ceases to work.

According to this invention, a lubricator of the type described has combined with a pressure-chamber through which the lubricant is forced to one or more feed-conduits, a member whose position controls the admission of steam to the feed-conduit or conduits, but which is itself yieldingly controlled in a direction to shut off the admission of steam thereto and has a face which is exposed to the pressure of fluid in the aforesaid pressure-chamber so that the pressure in such chamber when sufficiently high moves the member against its yielding control to admit steam.

Preferably, a plurality of pumps are provided to deliver lubricant into the single pressure-chamber and a plurality of conduits feed the lubricant from the said single pressure-chamber.

In the accompanying drawings which illustrate one method of carrying out this invention;

Figure 1 is a transverse section through the lubricator in the plane in which the automatically controlled steam-valve is disposed;

Figure 2 is a transverse section through the lubricator in a plane in which one of the sight-feeds is disposed;

Figure 3 is a longitudinal section through part of the lubricator; and

Figure 4 is a plan of part of the lubricator with the cover-plate removed from one half and having some details in section.

Like reference characters indicate like parts throughout the drawings.

The lubricator in general is of a known

type comprising a tank A in which is mounted a cam-shaft B which engages and operates a plurality of pump-plungers B¹. The tank is intended to be filled with lubricant and the pump-plungers thus draw in lubricant through perforations B² in their barrels and discharge it past non-return valves B³. Usually the barrels discharge into separate feed-conduits but in the apparatus employed for the purpose of the present invention they discharge into a pressure-chamber C which is common to all the barrels and is also common to a plurality of sight-feed devices D (Figure 2) each of which communicates with a feed-conduit D¹.

Steam under pressure is also admitted to the feed-conduits D¹ from a live-steam pipe E which has a branch E¹ from which ducts E² (Figure 2) communicate with each lubricant feed-conduit.

When the apparatus is not working a ball-valve E³ mounted in a housing F prevents the passage of steam from the conduit E to the conduit E¹ by resting under the action of gravity on the seating F¹. To automatically raise this valve when required and admit steam the following apparatus is employed:

A piston G is mounted in a barrel G¹ and is yieldingly controlled by a spring G² to keep it at the bottom of the barrel, as shown in the drawing. The piston has a stem G³ which extends out from the top of the barrel and enters the housing F of the valve E³ through a stuffing-box F². The housing F is spaced away from the barrel G¹ so that the stem has to extend across the space provided between the two and thus no leakage of steam past the stem in the housing can enter the barrel G¹.

The under-face of the piston G is exposed to the pressure of fluid, that is the lubricant, in the chamber C by means of a duct C¹ which communicates between the pressure-chamber C and the lower end of the barrel G¹.

The pressure-chamber C is provided with a spring-controlled relief-valve C³ past which lubricant can be returned through a duct C⁴ to the main lubricant-chamber.

The operation of this apparatus is as follows:

When the shaft B is rotating lubricant is continuously pumped into the pressure-chamber C and passes thence through the

sight-feed devices D to the feed-conduits D¹ and at normal working the pumps supply lubricant in sufficient quantity to maintain a pressure in the chamber C which is sufficient to raise the piston against the action of its spring G² so that the valve E³ is lifted off the seating F¹. Live steam is thus allowed to flow from the conduit E through the conduits E¹ and E² to the delivery-conduit D¹ where it mixes with the lubricant and travels forward to the parts to be lubricated. Any excess pressure is relieved by the valve C³ but as soon as the shaft B ceases to rotate, the piston G will commence to 10 turn under the action of its spring G² (the lubricant, meantime, still flowing from the pressure-chamber C out through the sight-feed devices) until the ball E³ once more rests upon the seating F¹ and the steam-supply is then cut off.

It will be seen that the steam-control in this lubricator is entirely automatic and the parts involved are easy to manufacture and such as are not liable to get out of order.

Obviously, the automatic steam-control device can be used with a single pump and a single delivery-conduit, but where a lubricator is supplying a number of points in a single mechanism, such as a locomotive, it is desired to shut off the steam for all the feed-conduits simultaneously and thus the apparatus described is admirably suited for use with a plurality of feed-conduits supplied with steam through a single controlled valve.

What I claim as my invention and desire to secure by Letters Patent is:—

1. In a lubricator the combination with a pump for lubricant, a pressure-chamber into which the pump delivers the lubricant and whence it is fed to the part to be lubricated, a valve for admitting steam to the lubricant on its way to the part to be lubricated, a yieldingly controlled member having operative connection with the valve, the yielding control operating in such direction as to move the member for closure of the valve, said member having one face opposed to thrust exerted by the fluid in the pressure-chamber, which face is so disposed that such thrust tends to move the member against its yielding control to open the steam-valve, substantially as set forth.
2. In a lubricator the combination with a plurality of pumps for lubricant, a single pressure-chamber into which all the pumps deliver the lubricant and whence it is distributed to the various parts to be lubricated, a single valve for controlling the admission of steam to the lubricant on its way to

the parts to be lubricated, a yieldingly controlled member having operative connection with the valve, the yielding control operating in such direction as to move the member for closure of the valve, said member having one face opposed to thrust exerted by the fluid in the pressure-chamber, which face is so disposed that such thrust tends to move the member against its yielding control to open the steam-valve, substantially as set forth.

3. In a lubricator the combination with a pump for lubricant, a pressure-chamber into which the pump delivers the lubricant and whence it is fed to the part to be lubricated, a valve for admitting steam to the lubricant on its way to the part to be lubricated, a housing for the said valve, a yieldingly controlled piston, a barrel in which the said piston works and at one end of which it tends to be kept by the said yielding control, which barrel is spaced away from the said housing for the valve, a conduit communicating with the interior of the barrel at that end of which the piston tends to be kept and with the pressure-chamber aforesaid, so that one face of the piston is exposed to the pressure of the lubricant in said chamber, and a stem operatively connected to the piston extending out from the barrel and having operative connection through a stuffing-box in the housing for the steam-control valve with the valve therein, substantially as set forth.

4. In a lubricator the combination with a pump for lubricant, a pressure-chamber into which the pump delivers the lubricant and whence it is fed to the part to be lubricated, a ball-valve for admitting steam to the lubricant on its way to the part to be lubricated, a housing for said ball-valve providing a seating on which the ball rests when steam is not to pass to the lubricant, a yieldingly controlled piston, a barrel for the piston spaced away from the housing for the ball-valve, the yielding control tending always to keep the piston at one end of its barrel, a conduit connecting the interior of the barrel at that end at which the piston tends to be held by its yielding control with the interior of the pressure-chamber and a stem on the piston which projects out from the barrel and extends through a stuffing-box in the housing for the ball-valve at a point beneath the ball-valve to lift the latter from its seating when the piston is moved against its yielding control, substantially as set forth.

In testimony whereof I affix my signature.
JOHN BLISS.
